UNITED STATES PATENT OFFICE.

MARTIN J. DONER, OF ST. LOUIS, MISSOURI, ASSIGNOR OF ONE-THIRD TO
MOSES H. ALEXANDER, OF ST. LOUIS, MISSOURI.

CAR-BRAKE.

SPECIFICATION forming part of Letters Patent No. 727,108, dated May 5, 1903.

Application filed July 17, 1902. Serial No. 115,911. (No model.)

To all whom it may concern:

Be it known that I, MARTIN J. DONER, a citizen of the United States, residing in St. Louis, in the State of Missouri, have invented certain new and useful Improvements in Car-Brakes, of which the following is a full, clear, and exact description, reference being had to the accompanying drawings, forming part of this specification.

10 My invention relates to that class of car-brakes wherein frictional shoes are utilized for braking action, the construction, briefly stated, consisting of brake-wheels carried by the car-axles, sectional brake-shoes adapted 15 to be brought into frictional contact with the brake-wheels, and novel mechanical means by which said shoes are moved to and from said brake-wheels.

The invention consists in features of novelty hereinafter fully described and claimed.

Figure I is a view, partly in elevation and partly in longitudinal section, of my brake applied to a car. Fig. II is a view, partly in plan and partly in horizontal section, of the 25 brake. Fig. III is an enlarged perspective view of one set of the brake-shoe sections. Fig. IV is an enlarged perspective view of the rack-gearing through the medium of which the brake-shoe sections are manipulated. Fig. V is a view, partly in elevation and partly 30 in section, of a modified brake-shoe section. Fig. VI is a perspective view of a portion of the brake-rod and the parts through which it is actuated.

35 1 designates the platform of a car; 2, the car-body bolster; 3, the truck-bolster, and 4 the cross-bar situated beneath the truck-bolster.

5 designates the car-wheels, and 6. their 40 axles.

7 designates brake-wheels rigidly mounted on the axles 6 and adapted to revolve therewith.

8 designates brake-shoe sections pivotally 45 united in series by hinge-pins 9, said sections being arranged around the periphery of the brake-wheels 7, so as to partially encircle said wheels. One of the end brake-shoe sections of each brake appliance is held by a 50 turnbuckle-link 10, which is pivoted to said

section and is also pivotally joined to the truck-bolster 3 through the medium of a bracket 11.

12 designates rocking levers provided with fork-arms 13, that straddle the brake-wheels 55 7 and are loosely mounted upon the axles 6.

14 designates connecting-rods containing turnbuckles, one end of each of which is connected to the end of the brake-shoe section 8, two of the connecting-rods on each side of 60 the brake-wheel being joined to the terminals of the end sections, and the remainder of the connecting-rods being joined to the sections at the hinge connections between them. The inner ends of the connecting-rods 65 are pivoted to the fork-arms 13 at intervals and so disposed as to position the rods obliquely with reference to the brake-shoe sections.

15 designates rack-bars that are pivotally 70 connected to the rocking levers 12 at 16. The upper ends of the rack-bars extend through openings formed in the truck-bolster 3, in which their movement is guided.

17 designates standards mounted on the 75 cross-bar 4 beneath the truck-bolster, and loosely positioned in said standards is a rock-shaft 18. On said rock-shaft is a pair of cog-segments 19, the teeth of which are adapted to mesh with the teeth of the rack-bars 15. 80 In Fig. II two frictional appliances are shown, to be operated by mechanism common to each, and in order that the two appliances may be actuated in unison the rack-bars 15 are situated both on the same side of the rock-shaft 85 18, and one of the rocking levers 12 is made longer than the other, so that it will extend to the far side of the rock-shaft. Fixed to the rock-shaft 18 is a two-armed lever 20.

21 is a link pivoted at one end of the upper 90 arm of the lever 20, and 22 is a link pivoted at one end of the lower arm of said lever.

23 is a bracket-arm attached to the truck-bolster 3.

24 is a double-armed lever having a fork 95 at its upper end, and 26 is a second double-armed lever having a fork 27 at its upper end. The link 21 is connected to the lower arm of the lever 24, and the link 22 is connected to the lower arm of the lever 26. 100

28 designates a brake-rod that extends from end to end of the car to connect with one or more of my brakes and to be operated from either end of the car. On the brake-rod are 5 collars 29 and 30, the former of which is adapted to bear against the fork of the lever 24, in which the brake-rod lies, and the latter of which is adapted to bear against the fork 27 of the lever 26, also occupied by the brake-rod. 10 31 designates a hand-lever swingingly mounted upon the car-platform and to which the brake-rod 28 is connected, there being one of said levers provided at each end of the car. The hand-lever is furnished with the latch 32, 15 that is adapted to engage a ratchet 33, the actuation of the latch being provided for by a pull-rod 34 and lever 35.

In Fig. V, I have shown a modification of the brake-shoe sections, wherein the section 20 8^a is recessed, and a supplementary block 8^b is placed in said recess and backed by a set-screw 8^c. By this construction the brake-shoe sections are relieved from wear, which is borne entirely by the supplementary blocks. 25

In the practical use of this brake the action of the parts is as follows: On a pull being exerted upon the hand-lever 31 in the direction indicated by the arrow in Fig. I the brake-rod 28 is moved toward the left, causing the 30 collar 29 on said rod to press against the lever 24. As a consequence a rearward pull is exerted upon the link 21, connected with said lever, and the rock-shaft 18 is moved to rock in the cog-segments upwardly. This upward movement of the segments elevates the rack-bars and raises the rocking levers 12, the fork-arms of which rock on the axles 6. On the rocking of said levers the connecting-rods 14 are carried therewith and the shoe-sections 8 are 35 pulled inwardly, causing them to bear against the peripheries of the brake-wheels 7 with frictional contact sufficient to afford any desired degree of braking action, according to the pull exerted upon the brake-rod 28.

The turnbuckles located in the connecting-rods 10 and 14 are placed therein to provide for the adjustment of the shoe-sections 40 8 with relation to the periphery of the brake-wheels 7 to regulate the amount of movement necessary to carry the shoe-sections to the 45 brake-wheels. All of the turnbuckles may be manipulated to obtain this adjustment; but I prefer to obtain it through the medium of the turnbuckle in the rod 10, inasmuch

as by so doing it is only necessary to manipulate a single buckle. 55

I claim as my invention—

1. In a car-brake, the combination with a car-axle, of a brake-wheel fixed to said axle, a series of shoe-sections movably positioned 60 at the periphery of said wheel, a rocking lever loosely mounted on said axle, means whereby said shoe-sections are connected to said rocking lever, and means for rocking said lever to move said shoes to said brake-wheel, substantially as described. 65

2. In a car-brake, the combination with an axle, of a brake-wheel fixed to said axle, shoe-sections movably positioned at the periphery of said brake-wheel, a rocking lever loosely 70 mounted on said axle, means for connecting said shoe-sections to said rocking lever, turnbuckle-rods adapted to hold said shoe-sections, and means for rocking said lever, substantially as described. 75

3. In a car-brake, the combination with an axle, of a brake-wheel fixed to said axle, a series of shoe-sections hinged to each other and arranged about the periphery of said brake-wheel, a rocking lever loosely mounted 80 on said axle, means whereby said shoe-sections are connected at their ends to said rocking lever, and means for rocking said lever. 85

4. In a car-brake, the combination with an axle, of a brake-wheel fixed to said axle, a 85 rocking lever loosely mounted on said axle, a series of shoe-sections movably positioned around said brake-wheel, means whereby said sections are connected with said rocking lever, and means for holding said shoe-sections 90 from rotation.

5. In a car-brake, the combination with an axle, of a brake-wheel fixed to said axle, a 95 rocking lever loosely mounted on said axle, a series of shoe-sections movably positioned around the periphery of said brake-wheel, means for connecting said shoe-sections to said rocking lever, a rack-bar connected to said rocking lever, a rock-shaft, a cog-segment on said rock-shaft arranged in engagement with said rack-bar, and means for rocking said shaft to operate said rack-bar and 100 rocking lever. 105

MARTIN J. DONER.
